UNITED STATES PATENT OFFICE.

HAROLD H. JEWETT, OF PUENTE, CALIFORNIA.

CAMP UTENSIL.

1,423,612.

Specification of Letters Patent. Patented July 25, 1922.

Application filed May 5, 1919. Serial No. 295,203.

To all whom it may concern:

Be it known that I, HAROLD H. JEWETT, a citizen of the United States, residing at Puente, in the county of Los Angeles and 5 State of California, have invented a new and useful Camp Utensil, of which the following is a specification.

My invention relates to camp utensils, being more particularly a device by means of 10 which several pots and pans may be supported from a single stake or standard and swung independently of each other in a circular path on the stake over a single fire or more as may be desired.

15 It is the principal object of my invention to produce a camp utensil of the character described, of simple form and construction, by means of which several articles may be placed over the fire at the same time independently of each other, such utensil being so constructed that it may be readily packed 20 to take up small space when not in use.

Other objects and advantages will appear hereinafter from the following description and drawings.

Referring to the drawings, which are for illustrative purposes only,

Fig. 1 is a perspective view of a utensil embodying a form of my invention.

30 Fig. 2 is an enlarged side elevation partly in section of the lower portion of the utensil shown in Fig. 1.

Fig. 3 is a plan view of the utensil shown in Fig. 1.

35 Fig. 4 is a fragmentary plan view partly in section showing a portion of an arm and its associated head.

Fig. 5 is a vertical sectional view on line 5-5, Fig. 4, and

40 Fig. 6 is a fragmentary view of the lower end of the stake showing the spider in folded position.

The utensil consists of a round stake or standard 11 preferably made of iron or similar material, the lower end of which terminates in a flattened spear or point 12 which is pushed into the ground for holding the stake in vertical position. To further aid in supporting the stake in vertical position 45 and permit considerable weight to be supported on the stake as hereinafter described, the stake is provided with a spider 13 consisting of a block 14 slidably mounted on the stake 11, being secured thereto in any desired position by means of a set screw 15.

Legs 16 are pivotally mounted as indicated

at 17 to the block 14, the outer end 18 of each leg being bent downwardly as clearly shown in Figs. 1 and 2.

Mounted on the stake above the spider 60 13 is a series of collars 20 each held in adjusted position on the stake by means of a set screw 21. Each collar 20 is provided with a reduced portion 22 upon which is swivelled a head 23, the head 23 in each 65 instance being held on its associated collar by turning over the upper end of the collar as indicated at 24 in Fig. 2, or in any other well known manner.

Each head 23 supports a horizontally extending arm in the form shown in the drawings the upper head supporting an arm 25, the lower head supporting an arm 26 and the intermediate head supporting an arm 27. The inner end of each arm 25, 26 75 and 27 is split as indicated at 28 in Figs. 4 and 5, the split being entered by the pointed end of a screw 29 on the head 23 whereby the arm is held securely in its associated head against turning and disengagement. 80

In the form shown the arm 25 terminates at its outer end in a fork 30 which supports a tray 31, the fork extending through a guide 32 formed on the under side of the tray whereby the tray is prevented from 85 upsetting. The arm 26 is provided with a flattened eye 33 formed on its outer end through which may be inserted the handle 34 of a skillet 35, a set screw 36 being provided on the eye 33 for securing the handle 90 therein. The outer end of the intermediate arm 27 is shaped to form a hook 37 suitable for supporting the bail 38 of a coffee pot 39.

The utensil above described is used in the following manner:

95 The pointed end 12 of the stake 11 is pushed or driven into the ground, the block 14 being fixed to the stake by the screw 15, the legs 16 are arranged into extended position and the stake driven into the ground 100 until the legs engage the surface of the ground as shown in Figs. 1 and 2. The collars 20 are then placed upon the stake and fixed thereon by means of their respective set screws 21 at the proper height from the ground and the desired distance from each other. The arm 25, 26 and 27 are then mounted in their respective heads 23 by means of the set screws 29 after which the various cooking utensils or trays are placed 105 upon the arms as above described.

It is readily apparent that each of the

arms with its load may swing freely in the path of a circle without interfering with the other arms. As shown in Fig. 1 the skillet is shown over the fire, the coffee pot 5 swung to one side and the tray on the arm 25 in convenient position to hold the fish or other thing to be cooked. It is to be understood that the coffee pot can be swung over the fire also or that two or more fires may 10 be made about the stake and each arm used for cooking over a different fire.

The long pointed spear 12 entering the ground in conjunction with the extended legs 16 of the spider engaging the surface of 15 the ground afford sufficient means for supporting the stake in upright position even when a maximum load is placed on the arms. The construction of the stake also 20 allows the utensil to be readily set up on uneven ground where the ordinary form of tripod cannot be readily or surely adjusted.

When the utensil is to be packed the

arms 25, 26 and 27 are removed from their respective heads and the stake removed from the ground, the legs 16 of the spider 25 assuming the position shown in Fig. 6.

I claim as my invention:—

A camp utensil comprising a stake having a pointed end arranged to enter the ground, a spider on said stake having outwardly extending pivotally mounted legs arranged to engage the ground, a series of collars slidably mounted on said stake, means for fixing said collars in adjusted position on said stake, a head rotatably mounted on each collar, an arm mounted in each head extending outwardly therefrom, and means for securing said arms in said heads to prevent turning of the arms in the heads.

In testimony whereof, I have hereunto set my hand at Los Angeles, California, this 30th day of April, 1919.

HAROLD H. JEWETT.
